VARIABLE DIRECTIONAL MOUTHPIECE FOR
EJECTORS

Pierre Jean Marchaut, Paris, France

Application March 6, 1934, Serial No. 714,215
In France January 13, 1934

6 Claims. (Cl. 299—130)

The subject of this invention is a variable directional mouthpiece for an ejector for the distribution of bodies or substances, or mixtures of substances, which can be used, for example, as a fire extinguishing device of the type in which one or more ejectors are suitably arranged to distribute an extinguishing body or substance, in any appropriate physical state, in the form of a conical sheet having a suitable apex angle, this continuous conical sheet forming a sort of extinguisher.

It comprises the combination of a nozzle and a valve of appropriate profile, one or other or both of them being susceptible to deformation in a suitable manner and movable relative to one another in such a way as to form, according to their relative position, a variable directional mouthpiece which permits the distribution of a fire-extinguishing medium, body substance or of a mixture of substances, in the form conical sheet for example, having a variable apex angle, with the object of ensuring the distribution of a suitable extinguishing substance, thus constituting a fire extinguishing device.

In the attached drawings, which represent, by way of an example of realization of the invention, one form of construction of an ejector with variable directional mouthpiece:—

Fig. 1 shows the nozzle of the ejector and its valve in the rest position,

Figs. 2, 3 and 4 show the ejector in different phases of operation,

Fig. 5 shows diagrammatically an example of the use of the ejector,

Figs. 6 to 8 show a variation, Fig. 7 being a section of VII—VII of Fig. 6.

According to the constructional example of the invention shown, the body 1 of the ejector, cylindrical for example, terminates in a nozzle 2 of variable internal section flaring or, suitably bell-mouthed, a valve 3 capable of being deformed and held by a tie piece or retaining member 4, for example, rigid or otherwise, and making contact at its periphery 9 with the internal flaring surface 45 of the nozzle 2.

The body is, naturally, connected by any appropriate means to a reservoir containing a substance or a mixture of substances, fluid, gas or other suitable ones, stored under suitable pressure and which can be distributed for fighting a fire.

The ejector is used in the following manner:—

The valve 3 being held by the retaining member 4 in the position of Fig. 1, if the substance to be distributed is admitted into the ejector in a suitable physical condition, fluid, gaseous, pow-

dered, in foam, or in a mixture, it exerts a pressure on the valve 3, the edges 9 of which become deformed and are no longer in contact with the nozzle 2. A passage is thus created between these elements, which forms the directional mouthpiece 5. When the valve 3 is in the position of Fig. 1 or 2, the mouthpiece 5 is such that, as can be seen from Fig. 2, the substance is distributed in the form of a conical sheet 6 having a very wide apex angle.

If, by means of the retaining member 4, the valve 3 is displaced in the nozzle 2, by taking it for example, to the position indicated in Fig. 3, this valve becomes deformed while still tending to make contact with the internal surface of the nozzle 2, but owing to the pressure of the fluid coming into the ejector, a mouthpiece 7 is again formed between the internal surface of the nozzle and the edges 9 of the valve. As will be seen, the conical sheet 8 into which the fluid is distributed, has a smaller apex angle than in Fig. 2.

Finally, if the valve 3 is brought by axial displacement into the position of Fig. 4, in which its periphery 9 comes against the cylindrical part of the body of the ejector, the mouthpiece 10 which is then formed, causes the distribution of the fluid in the shape of a sheet 11 sensibly cylindrical.

It will thus be seen that by the simple movement of the valve 3 (which can be deformed) along the nozzle 2 of the ejector, the distribution of the fluid projected can be effected in the form of a conical sheet whose apex angle is variable between any desired limits.

The ejector may also be formed in accordance with the variations indicated in Figs. 6 to 8; the nozzle 2 of the ejector carries ribs, projections or strips 15, longitudinal or otherwise, and of predetermined size, against which bears the edge 9 of the valve 3, which no longer bears directly on the actual interior surface of the nozzle, and as a result, there is always a passage existing between the valve and the nozzle, forming a directional mouthpiece, and the fluid which flows out is not compelled to create the mouthpiece 5, 7, or 10 for itself in order to pass. The shape and the arrangement of the strips 15 may be suitably designed to ensure at the same time the guiding of the fluid distributed. These strips could, of course, be arranged on the valve 3, on the nozzle and the valve, or even be replaced by any device enabling an annular passage to be maintained between the nozzle and the valve.

The valve 3 can be constructed in any desired manner and can be made, for example, of elas-

tic rubber, it being possible to return this valve to its original shape, that of Fig. 1, after use.

On the other hand, a device can be provided for returning the valve 3 to its original position, 5 it being possible to effect this return automatically by means of a spring, counterweight or the like, or again by the action of the fluid distributed itself on the valve or on a suitable device.

This valve could also be constructed of a metal 10 susceptible of being deformed, elastically or otherwise, subject always to the condition that the valve 3, during its displacement in the flaring nozzle 2, maintains a profile corresponding to that of the nozzle.

15 Again, the nozzle itself could be made so that it could be deformed, and not the valve 3, the variation in the mouthpiece formed by the nozzle and its valve being then obtained by the variation of shape of the nozzle itself under the 20 influence of the displacement of the valve, which latter might also be so formed that it could be more or less deformed.

In Fig. 5 is shown diagrammatically a method 25 of applying the ejector when used as a fire extinguishing device and applied to a chamber, ships cabin or the like.

The ejector 1 is fixed to the upper part of the chamber 12, in its centre for example, in such a way that by simple operation of the apparatus 30 the extinguishing body can be distributed in the form of a conical sheet having a variable apex angle, which reaches to all parts of the chamber. The actuation of the valve 3 could naturally take place from the outside by any suitable control 13. 35 The device arranged in this manner thus permits the distribution of any desired extinguishing body, in any suitable physical state, simple or in a mixture, in the form of a conical sheet which, forming a surface which is sensibly airtight, constitutes a sort of extinguishing cap which isolates the zone contained inside the sheet from the exterior atmosphere. In this way it is possible to distribute, for example, an extinguishing medium in the form of a powder carried by a gas, preferably inert, such as carbonic anhydride, for example; this gas then rapidly replacing the air contained in the cone limited by the sheet, contributes largely to the efficiency of the device used as a fire extinguisher. The fire is attacked simultaneously by the suppression of air required for combustion and by the sprinkling with the extinguishing powder or other suitable substance, which can act directly on the burning material itself.

55 The invention is applicable to fire extinguish-

ing devices and also to the distribution, medium or any body of substance for all purposes.

What I claim is:—

1. A variable directional ejector mouthpiece for a fire extinguishing device, comprising in combination, a nozzle and a valve member therefor forming a pair of cooperating members, of which pair one member is movable with respect to the other and deformable to produce, according to their relative positions, an ejected conical sheet 10 of fire extinguishing medium having a variable apex angle, and means for moving said one member.

15 2. A variable directional ejector mouthpiece for a fire extinguishing device, comprising in combination, a nozzle and a valve member therefor forming a pair of cooperating deformable members, of which pair one member is movable with respect to the other so as to produce, according to their relative positions, an ejected conical 20 sheet of fire extinguishing medium having a variable apex angle, and means for moving said one member.

25 3. A variable directional ejector mouthpiece according to claim 1, wherein one end of the nozzle is flared while the valve member is capable of being drawn toward and into the flared end of the nozzle to provide for the alteration of the apex angle of the ejected medium.

30 4. A variable directional ejector mouthpiece according to claim 2, wherein one end of the nozzle is flared while the valve member is capable of being drawn toward and into the flared end of the nozzle to provide for the alteration of the apex angle of the ejected medium.

35 5. A variable directional ejector mouthpiece for a fire extinguishing device, comprising in combination, a rigid nozzle having a flaring end, a valve member of resilient material disposed adjacent to said flaring end, and means for moving said valve member into and retaining the same in different positions with respect to the flaring end of the nozzle so as to cause the profile of the valve member to adapt itself to the interior surface of said flaring end and together with the same produce an ejected conical sheet of issuing medium having one of a large range of various apex angles.

40 6. A variable directional ejector mouthpiece according to claim 5, wherein ribs are disposed upon the interior surface of the flaring end of the rigid nozzle to space the edge of the valve member a slight distance from said surface.

PIERRE JEAN MARCHAUT.
